Primary Examiner — Antoine Duval Davis

(73) Assignee: **LS ELECTRIC CO., LTD.**, Anyang-si (KR)

(74) Attorney, Agent, or Firm — K&L Gates LLP

(**) Term: **15 Years**

(57) **CLAIM**

(21) Appl. No.: **29/804,954**

The ornamental design for a wireless thermal sensor for electric power device, as shown and described herein.

(22) Filed: **Aug. 24, 2021**

(30) **Foreign Application Priority Data**

DESCRIPTION

Feb. 25, 2021 (KR) 30-2021-0009710

(51) **LOC (14) Cl.** **10-04**

(52) **U.S. Cl.**

USPC **D10/52**

See application file for complete search history.

(56) **References Cited**

FIG. 1 is a front perspective view of a wireless thermal sensor for electric power device showing the new design;
FIG. 2 is a rear perspective view thereof;
FIG. 3 is a front view thereof;
FIG. 4 is a rear view thereof;
FIG. 5 is a left-side elevation view thereof;
FIG. 6 is a right-side elevation view thereof;
FIG. 7 is a top plan view thereof; and,
FIG. 8 is a bottom plan view thereof.
